UNITED STATES PATENT OFFICE

WILLIAM F. BRÜGMANN, OF EVANSTON, ILLINOIS

PRINTER'S REGISTER HOOK

Application filed June 20, 1927. Serial No. 199,949.

This invention relates to improvements in register hooks for holding printing plates in position upon a base and for adjusting the same, and one of the objects of the invention is to improve and simplify the construction of the hook, and at the same time provide a sturdy construction in which the parts may be readily assembled and which hook may be readily placed in position within a groove 5 in the base from the upper face of the base.

A further object is to provide an improved hook of this character which is provided with improved means for locking or securing the same against accidental removal from the groove in the base, but which will permit a micrometer adjustment of the same, the locking and securing means being so constructed or shaped that the hook may be readily moved in the groove in one direction and may be 10 readily removed by raising one end of the hook to cause the locking means to be rendered inactive or shifted to an inactive position by engagement of the locking means with a portion of the wall of the groove by the 15 tilting or raising movement of one end of the hook.

A further object is to reduce the size and width of the hook, thereby rendering it possible to provide a greater number of grooves 20 in the base than has heretofore been possible with the use of other hooks, while at the same time the power and strength of the hook will not be impaired or reduced.

A further object is to provide improved 25 locking means for locking the adjusting means against retrograde movement in the groove and which locking means is adapted to be rendered inactive by the insertion of the key for adjusting or operating the hook.

A further object is to provide an improved 30 construction and arrangement of groove and rack in the base to provide a settling space for cleaning liquid and foreign particles.

To the attainment of these ends and the accomplishment of other new and useful objects 35 as will appear, the invention consists in the features of novelty in substantially the construction, combination and arrangement of the several parts, hereinafter more fully described and claimed and shown in the accom-

panying drawings illustrating this invention, and in which

Figure 1 is a side elevation of a hook of this character constructed in accordance with the principles of this invention.

Figure 2 is a right hand end elevation of Figure 1.

Figure 3 is a top plan view of Figure 1.

Figure 4 is a horizontal sectional view taken on line 4—4, Figure 1.

Figure 5 is a vertical, sectional view taken on line 5—5, Figure 3.

Figure 6 is a vertical, sectional view taken on line 6—6, Figure 1.

Figure 7 is a detail perspective view of 65 one end of the body of the hook, with parts removed.

Figure 8 is a detail perspective view of one end of the locking members.

Figure 9 is a top plan view of a base with 70 one of the hooks in position thereon.

Figure 10 is a detail sectional view taken on line 10—10, Figure 5, with parts omitted.

Figure 11 is a view similar to Figure 5 75 with parts broken away, and parts omitted, showing the manner of inserting the key for adjusting the hook.

Figure 12 is a detail perspective view of the locking member for the adjusting gear or worm.

Figure 13 is a detail perspective view of a portion of one form of rack to be used in the base plate.

Figure 14 is a top plan view of a rack similar to the rack shown in Figure 13.

The hook consists essentially of a body portion 15, which is rectangular in configuration and comparatively narrow. Swiveled to the body portion, and adjacent one end thereof, so as to project thereabove, is a plate engaging member or clamp 16 which is preferably considerably wider than the width of the body portion 15, a portion of the member 16 being reduced as at 17 and rounded so as to fit within a socket 18 opening through the top of the body portion. The plate engaging member is held against displacement preferably by means of pins or fastening members 19—20, which engage in an annular

groove 21 in the portion 17 and also in seats 22, which co-operate with the groove 21.

A worm 23 is arranged uprightly in the socket 18 beneath the plate engaging member, 5 and one end of the worm rests upon the base 24 of the socket. The worm 23 is provided with an opening 25 therein which is angular in cross section, and this opening 25 registers with an opening 26 in the plate engaging 10 member 16, so that a tool or implement 27 having its extremity 28 angular in cross section to correspond with the shape of the opening 25 in the worm 23, may be inserted through the opening 26 and into the opening 25 for rotating the worm 23 with respect to the plate engaging member 16.

The upper extremity of the worm 23 is reduced as at 29, and one portion of this reduced portion is preferably flattened as at 30 (see Figure 10) so that when a ratchet wheel 31 is placed upon the reduced portion 29, a flat portion 32 in the ratchet wheel 31 will co-operate with the flat face 30 of the reduced portion 29, to secure the ratchet wheel to the 25 worm 23 for rotation therewith.

A locking member 33 is provided with a circular recessed extremity 34 and a depending formation 35 which latter acts as a pawl to co-operate with the teeth of the ratchet wheel 31. The portion 35 is preferably formed by being struck out of the body portion of the locking member and deflected so as to engage into the teeth of the ratchet.

The other extremity 36 of the locking member 33 is engaged by a spring 37, the spring being secured to one end of the body portion 15 by a suitable fastening device, such as a screw 38.

The normal tendency of the spring 37 is to 40 move the locking member in a direction that the pawl 35 will engage in the ratchet teeth of the ratchet wheel 31 and the circular end 34 registers with the opening 26 in the plate engaging member 16 and projects partially 45 over the opening 25 in the worm 23 so that when the tool 27 (see Figure 11) is inserted in the opening 26, a portion of the tool will engage the circular end 34 of the locking member 33 and move the latter backwardly so as 50 to cause the pawl or formation 35 to move out of engagement with the teeth of the ratchet 31 and against the stress of the spring 37.

This operation is caused at the time that the 55 angular extremity 28 of the tool is entering the angular shaped recess 25 of the worm 23.

When the worm 23 is thus released or unlocked the worm may be rotated by the tool. When, however, the tool is not inserted, the 60 spring 37 will move the locking member 33 in a direction to cause the pawl or formation 35 to engage the teeth of the ratchet 31 and thereby lock the worm 23 against rotation. This locking movement will hold the entire 65 hook against retrograde movement, but when

released the worm 23 serves as a means for producing a micrometer adjustment.

Co-operating with the worm 23 is a worm gear 39, the teeth of which mesh with the worm, and the gear 39 is rotatable about a horizontal axis. A portion of the body 15 is cut away or milled out as at 40 to form a chamber for the gear 39 and a laterally projecting stud 41 is arranged within the chamber 40 and upon which stud the gear 39 is 75 sleeved.

In the present form of the invention the stud 41 is shown as being formed integrally with the body portion 15, but it is to be understood that this stud may be formed separately and fastened to the body portion. The stud is of a length just slightly greater than the thickness of the gear 39 and both will be housed and stand within the chamber 40 so that one side of the gear 39 will be 80 protected by a solid wall formed by a portion of the body 15.

The gear 41 is held against displacement by means of a screw or bolt 42 which is threaded into the stud, the head 43 of the bolt being 85 of a diameter somewhat greater than the external diameter of the stud, thereby serving as a means for preventing the gear 39 from being detached from the stud 41.

The teeth of the gear 39 project beyond 90 the bottom of the body portion 15, through an opening 44 in the bottom of the body 15 which communicates with the chamber 40. With this construction it will be manifest that when the worm 23 is rotated the gear 39 will 100 be correspondingly rotated.

Fastening members 45 are provided for the hook and these fastening members are arranged side by side, adjacent the top of the body portion 15 and are mounted by one extremity as at 46, to the body portion, so that the other extremities 47 of the locking members may be projected laterally beyond the sides of the body 15 and may be compressed or moved together towards each other so that they will not project beyond the sides of the body, for a purpose to be set forth.

The body portion 15 is provided with recesses 48 opening through the sides thereof adjacent one end and communicating with the extremities of the recess 48 are reduced recesses 49—50 also opening through the side faces of the body 15. The reduced recess 49 opens through the end of the body 15 and each of the recesses 49 has communication with recesses 51 opening through the end of the body 15. The recesses 51 are separated by means of a partition 52.

The recesses 49 and 50 are of a width just 125 slightly greater than the width of the locking members 45, the ends of which fit within the respective recesses 49 and 50, while the recess 48 intermediate the recesses 49—50 are of a width somewhat greater than the 130

width of the adjacent portion of the locking members 45. This provides for space for dirt accumulations and will tend to keep the catch in service a greater length of time without necessitating cleaning.

Depending from the free extremities of the locking members 45 are projections 53 which project into the recesses 51 and co-operate with the walls of the recesses 51 for limiting the outward movement of the locking members and also serve to limit the inward movement of these members.

A resilient element 54 preferably in the form of a coil spring, is disposed between the locking members 45 and passes through a recess 55 in the body portion 15. The resilient element 54 tends normally to swing the locking members 45 outwardly and away from each other to cause them to project beyond the lateral faces of the body portion 15, but may be compressed so as to permit the locking members to be pressed inwardly.

The lower faces of the locking members are beveled as at 56 for a purpose to be set forth, and the upper faces 57 are rounded as shown more clearly in Figures 1 and 2, for a purpose to be set forth.

The catch thus formed is adapted to be seated in a groove 58 in a base plate 59 and the grooves 58 open through the top of the plate and are shaped to form overhanging flanges 60, see particularly Figure 6.

The grooves are also provided with lateral projections 61, adjacent but spaced above the bottom of the groove which project inwardly, and these projections 61 serve as a means for maintaining the hook against lateral displacement within the groove.

Within the groove is arranged a rack 62 which may be secured in position in any suitable manner such as by means of fastening screws 63 passing through the bottom of the base and engaging the rack.

The rack 62 is of a width considerably less than the width of the groove and the teeth 64 of the rack are cut considerably deeper than the height of the teeth of the gear 39 which co-operate with the rack, as shown more clearly in Figures 5 and 6. The teeth 64 of the gear 39 and the teeth 64 of the rack 62 are flat faced, and by providing the space between the teeth 64 and all the teeth of the gear 39 pockets will be formed for receiving dirt accumulation and by arranging the rack 62 in the center of the bottom of the groove a gutter will be formed in the bottom of the groove on each side of the rack to accommodate dirt.

In Figures 13 and 14 there is shown another form of rack which embodies longitudinal side members 65 which support the teeth 66 by their extremities so as to form a grid to produce spaces for dirt accumulation.

In use, the spring 54 tends normally to hold

the locking members 45 projected beyond the sides of the body 15.

The hook is placed into the groove in close proximity to the work and by depressing the body portion 15 the beveled faces 56 of the locking members 45 engaging the side walls of the groove will force the locking members inwardly and thereby permit the hook to be lowered into the groove.

When the hook is thus seated the spring 55 will then project the locking members 45 to cause them to engage beneath the overhanging flanges 60 of the groove. The hook will then be seated in the groove and may be moved forwardly and backwardly in the groove by the insertion of the tool 27 into the opening 26 in the plate engaging member 16. This will unlock the worm 23 and by rotating the tool either forwardly or backwardly the hook may be advanced or retracted. Immediately upon removing the tool 27 the hook will be locked against retrograde movement.

In order to remove the hook, the operator may engage a tool in a recess 67 formed in the rear end of the body 15 and by prying up or raising the rear end of the body portion 15 the hook may be removed from the groove. This will be permitted by reason of the rounded upper portion 57 of the locking members 45 engaging the edges of the overhanging portions 60 of the groove 58 in the base as the rounded portion contacting with the edge of the groove will cause the members 45 to be forced inwardly against the stress of the spring 54 during the raising of the rear end of the hook.

With this improved construction a very narrow hook may be provided and on the basis of ten grooves to a standard 24 by 24 pica mounting base, the groove for the hook will occupy only about one-fourth of an inch and the plate support strip will then be approximately five-sixteenths of an inch wide.

It will also be manifest that with this improved construction there is provided a lock in each hook which is thrown out of engagement by the insertion of the operating key and by the removal of the key the hook will be automatically locked. Furthermore, with this improved construction the washing fluid and the ink will not clog or obstruct the operation of the hook as the fluid will find its way down the side walls to the bottoms of the grooves into a settling space.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A printer's register hook embodying a

- body portion, locking members carried by the said body and adapted to be projected laterally beyond the sides of the body, and means tending normally to project said members, a portion of the upper face of said members being shaped to cause the members to be retracted by the engagement of such face with the edge of the groove in the base member as one end of a catch is being raised out of the groove.
2. A printer's register hook embodying an adjustable plate clamping device, means for adjusting said device, the said means embodying a gear element rotatable about an upright axis, a ratchet carried with said gear, a locking member co-operating with the ratchet for locking the gear, means tending normally to render the locking member active, in combination with an operating device adapted to be inserted into the device for rotating the gear, said locking member being adapted to be rendered inactive by the insertion of said operating device.
3. A register hook embodying a body, a gear mounted upon the body for propelling it, said body having grooves opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body.
4. A register hook embodying a body, a gear mounted upon the body for propelling it, said body having recesses opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body, the lower faces of said members being beveled whereby said members will be forced into said recesses against the stress of said resiliently yielding means when said beveled faces are forced against the edge of a receiving groove for the hook by the insertion of the hook into said groove.
5. A register hook embodying a body, a gear mounted upon the body for propelling it, said body having recesses opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body, the upper faces of said members being rounded or beveled whereby said members will be forced into said recesses against the stress of said resiliently yielding means by the engagement of said faces against a portion of a groove in which the body may be seated, by the raising movement of one end of the body out of said groove.
6. A register hook embodying a body, a gear mounted upon the body for propelling it, said body having recesses opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body, and means for limiting the outward movement of said members.
7. A register hook embodying a body, a gear mounted upon the body for propelling it, said body having recesses opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body, a formation projecting from the free end of each of said members, and recesses in which said formations operate, the outward movement of said members being limited by the engagement of said formations with the walls of the last said recesses.
8. A register hook embodying a body portion, a chamber formed therein and opening through one of the lateral walls of the body, a stud connected with one wall of the chamber and projecting thereinto, a propelling gear rotatably mounted upon said stud, the teeth of said gear projecting below the bottom of said body as the gear is rotated, a fastening member entering said stud for holding the gear against displacement, and means for rotating the gear.
9. A register hook embodying a body, a gear mounted upon the body for propelling it, said body having recesses opening through the lateral walls thereof, a locking member disposed in each of the grooves, said members being pivotally mounted adjacent one end whereby the members will swing in horizontal planes, and resiliently yielding means disposed between the said members and operating to project the free ends of said members beyond the adjacent lateral walls of the said body, a portion of said recesses being of a width considerably greater than the height of the adjacent portion of said locking members to provide spaces for the reception of dirt accumulations.
10. A register hook embodying a body, a

- gear mounted thereon for propelling it, yielding locking members extending beyond the lateral walls of the body, in combination with a base having a groove to receive the hook, 5 overhanging portions on the walls of the groove under which said members engage to lock the hook in the groove, and a recess opening through the end of the body for the reception of the end of an implement whereby 10 by the hook may be removed from the groove by raising said recessed end.
11. A register hook embodying a body, locking members adapted to extend beyond the lateral walls of the body, resiliently yielding means for normally projecting said members, depending ears on the free ends of said members, recesses in the body in which the ears operate, said ears engaging the walls of the recess to limit the outward movements 15 of the locking members, and a recess opening through the end of the body for the reception of the end of an implement whereby the hook may be removed from the groove in a base by raising said recessed end.
12. A register hook embodying a body, means for propelling the body embodying a worm rotatable about an upright axis, a ratchet wheel connected with the worm, said worm being recessed to receive an operating 20 tool, a locking member movable transversely of the worm, a dog on said member to engage the teeth of the ratchet, and resiliently yielding means tending normally to move the locking member to cause the dog to engage the ratchet teeth, a portion of said member extending partially across the recess in said worm whereby the insertion of said operating tool will shift the locking member against the stress of said resiliently yielding member 25 to release the ratchet and worm.
13. A register hook embodying a body portion, and yieldable locking means carried by the body and adapted to engage under shoulders projecting over a groove in a base in which the hook is adapted to be seated to lock the hook against raising with respect to the base, there being a recess opening through the rear end of the body for the reception of an implement to raise said end of the hook out of the groove.
14. A register hook embodying a body portion, yieldable locking means carried by the body and adapted to engage under shoulders projecting over a groove in a base in which the hook is adapted to be seated to lock the hook against raising with respect to the base, and a shoulder formed on the rear end of the hook beneath which an implement may be placed to raise said end of the hook 30 out of the groove, said shoulder being disposed within the plane of the end of the hook.
15. A register hook embodying a body, means carried by the body for propelling it, locking means for the said propelling means
- located entirely thereabove, and means providing for the application of an operating implement for actuating the said propelling means, the said locking means being rendered inactive in advance of the application 70 of the said implement to the propelling means.
16. A register hook embodying a body, means carried by the body for propelling it, locking means for the said propelling means 75 and located thereabove, means tending normally to render the said locking means active, and means providing for the application of an operating implement for actuating the said propelling means, the said locking means being rendered inactive in advance of the application of the said implement to the propelling means.
17. A register hook embodying a body, means carried by the body for propelling it, locking means for the said propelling means, and means providing for the application of an operating implement for actuating the said propelling means, the said locking means being rendered inactive in advance of the application of the said implement to the propelling means.
18. A base having a groove therein, a rack in the bottom of the groove, a register hook embodying a plate clamping catch adapted to be seated in the groove, a propelling gear connected with the hook and engaging the rack, and means for rotating the said propelling gear, said rack being disposed in the bottom of the groove in a position to form a dirt receiving space on each side of the rack.
19. A register hook embodying a body portion, a chamber formed therein and opening through one of the lateral walls of the body, a stud connected with one wall of the 100 chamber and projecting thereinto, a propelling gear rotatably mounted upon said stud, the teeth of said gear projecting below the bottom of said body as the gear is rotated, means for securing the gear against displacement with respect to the stud, and means for rotating the gear.
20. A printer's register hook embodying a body, a gear mounted upon the body for propelling it, a driving gear for actuating said propelling gear, and a ratchet device operating to hold said gearing against retrograde movement, said ratchet device embodying a flat leaf spring for holding the ratchet engaging member.
21. A printer's plate mounting device embodying a base having a groove, a rack in the groove, a register hook, a gear carried by the hook for engagement with said rack, a driving gear for actuating the propelling gear, a ratchet device operating to hold the gearing against retrograde movement, said ratchet device embodying a ratchet engaging member, and a flat spring for yieldingly holding said ratchet engaging member.

22. A printer's register hook embodying a body, a worm wheel mounted upon said body for propelling it, a worm meshing with said wheel, a separate toothed member connected with the said worm, and a ratchet device co-operating with said separate member.

23. A printer's register hook embodying a body, a worm wheel mounted upon said body for propelling it, a worm meshing with said wheel, teeth connected with said worm and separate from the threads forming the worm, and a ratchet device co-operating with the said separate teeth.

5 In testimony whereof I have signed my name to this specification, on this 9th day of June, A. D. 1927.

WILLIAM F. BRÜGMANN.
